M. J. ROSENBERG

KNICKERS

Filed Aug. 3, 1926

Maurice J. Rosenberg, INVENTOR.

BY

ATTORNEY.

Geo. P. Kimmel.

UNITED STATES PATENT OFFICE.

MAURICE J. ROSENBERG, OF BALTIMORE, MARYLAND.

KNICKERS.

Application filed August 3, 1926. Serial No. 126,841.

This invention relates to apparel, more particularly to a garment of the knickers type designed primarily for women's and misses' wear, and the object of the invention 5 is to provide, in a manner as hereinafter set forth, a garment of the type referred to with new and novel means for gathering the waist thereof to adjust the size of the latter for the purpose of retaining the knickers in position when worn and further for holding the gathered portions of the waist.

A further object of the invention is to provide, in a manner as hereinafter set forth, a garment of the type referred to having 15 means at the back thereof for gathering the waist to adjust the size of the latter for the purpose referred to and further with adjustable means for concealing the gathered portions of the waist.

Further objects of the invention are to provide, in a manner as hereinafter set forth, a garment of the type referred to, which is simple in its construction and arrangement, strong, durable, distinctive in appearance, 20 conveniently opened and closed when worn, readily adjusted for fitting the waist of the wearer, and comparatively inexpensive to manufacture.

With the foregoing and other objects in 30 view, the invention consists of the novel construction, combination and arrangement of parts, as hereinafter more specifically described and illustrated in the accompanying drawings, wherein is shown an embodiment 35 of the invention, but it is to be understood that changes, variations and modifications can be resorted to which fall within the scope of the claim hereunto appended.

In the drawings wherein like reference 40 characters denote corresponding parts throughout the several views:

Figure 1 is a fragmentary view, in front elevation, of a garment in accordance with this invention, with the waist in non-adjusted position and the garment partly open.

Figure 2 is a fragmentary view, in rear elevation, of a garment in accordance with this invention and with the waist in a non-adjusted position.

Figure 3 is a section on line 3—3 Figure 2.

Figure 4 is a section on line 4—4 Figure 2.

Figure 5 is a fragmentary view, in rear elevation of a modified form.

Figure 6 is a section on line 6—6 Figure 5. A garment of the type referred to in ac-

cordance with this invention, comprises a front portion 1 and a back portion 2. The portions 1 and 2 are secured together, and so shaped to provide a pair of legs 3, 4 a crotch 5, combined thigh and hip portions 6, 7 and a waist portion 8. The back portion 2 at its upper end is formed with a pair of oppositely disposed flaps 9, 9' which are arranged forwardly with respect to the back portion 2 and are overlapped by the front portion 1. The upper part of the front portion 1 is normally disconnected from the back portion 2 and the disconnected part of the front portion 1 is of the same height as the height of the flaps 9 and is indicated at 11. The front portion 1 is formed of two plies of suitable material secured together as at 11 and the back portion 2 is formed of two plies of suitable material secured together as at 12. The front portion 1 is secured to the back portion 2 as at 13. The front portion 1 at one side thereof and near its upper end is provided with a pocket 14.

Secured to the inner face of the part 10 of the front portion 1 and co-extensive with the width of the latter is a lining member 15 of a width materially less than the height of the part 10 and said lining member 15 is flush with the top and side edges of the part 10. The lining member 15 provides a reinforcement for the upper end of the front portion 1. At each end of the part 10 a set of button holes is formed and as shown the set consists of three button holes. The button holes of each set are indicated at 16 and which associate with the buttons 17 formed on the forward face of the flaps for the purpose of detachably connecting the part 10 to the back portion 2, see Figure 1. 85

Secured to the inner face of the back portion 2 at the top thereof and of a length co-extensive with the width of said back portion, is a lining member 18 of appropriate width and which is connected to the inner face of the back portion 2 in a manner to provide a pocket 19. The lining member 18 is slitted as at 20, 21 to form a pair of spaced inlets or mouths for the pocket 19. Anchored at one end, as at 22 to the rear wall of the pocket 19 is a shirring or pull string 23 which extends through the opening 20 and anchored within the pocket 19, as at 24 is a shirring or pull string 25 which extends through the opening 21. The shirring strings 23 and 25 are oppositely disposed with respect to each other. Posi- 100 105 110

tioned against the outer face of the back portion 2, centrally thereof, is a concealing strip 26 having the intermediate portion of its lower edge fixedly secured to the back portion 2 by a row of stitching 27. The row of stitching 27 is of less length than the length of the bottom edge of the strip 23 and terminates at points adjacent the end of said strip 26 thereby setting up said strips 10 with a pair of free terminal portions 28, 29 and each of the latter is provided with a button hole 30. Secured to the outer face of the back portion 2, is a series of spaced buttons 31 which are interposed between the strip 26 and the back portion 2 and associate with the button holes 30 for adjustably connecting the free end terminal portions of the strip 26 to the back portion 2. The strip 26 is provided for concealing and holding the gathered portions of the garment arranged centrally of the top of the back portion 2 when the shirring strips are operated to reduce the size of the waist portion 8 of the garment.

25 With reference to Figure 5, the concealing strip is indicated at 32 and instead of it being connected at its lower end to the back portion 2 of the garment, it is connected at its vertical median as indicated at 33.

30 Otherwise than that as stated the strip 32 is constructed similar to the strip 26 and performs the same function.

The strips 26 and 32 further act as means for maintaining the back portion 2 when gathered due to engagement of the end terminal portions of either of said strips with certain of the buttons 31. After the back portion 2 has been gathered the strip 26 is connected therewith by a pair of buttons in 35 association with the button holes 31 and the gathered portions between the said pair of buttons is prevented from being separated by either of said strips. This maintains the waist portion of the garment in its adjusted 40 position. Therefore the strips 26 and 32 not only provide means for concealing the gathered portions centrally of the back portion 2 but further prevent the separation of said gathered portions and under such conditions maintaining the waist part 8 in its 45

50

adjusted position. The shirring strings can also be tied together which acts as a further means for maintaining the waist part 8 in adjusted position. The adjusting of the size of the waist of the garment is had solely at the back thereof. The front of the garment, at the waistline, is never gathered when adjusting the size of the waist, as the front portion 1 at the part 10 thereof is always extended. The part 10 of the front portion 1 acts as a closure for the garment and permits of the readily positioning of the garment on the wearer. The strips 26 or 32 can also be employed for adjusting the size of the waist by the engagement of the strips with the buttons 31. In this connection a part of the portion 2 can be gathered and either strip employed to maintain such part in gathered position.

It is thought that the many advantages of a garment, of the type referred to, and in accordance with this invention can be readily understood, and although the preferred embodiment of the invention is as illustrated and described, yet it is to be understood that changes in the details of construction can be had which will fall within the scope of the invention as claimed.

What I claim is:

A garment of the type referred to comprising front and back portions connected together, said back portion having its inner side at the upper part thereof formed with a pocket, a pair of oppositely disposed shirring strings anchored in and extended from said pocket for gathering a part of the back portion, a combined gathered portion concealing and retaining strip secured to the outer face of said back portion and formed with free end terminal portions normally disconnected from said back portion, and said back portion and end terminal portions having co-acting means for detachably connecting said terminal portions to said back portion to maintain the gathered part of the back portion from extending.

In testimony whereof, I affix my signature hereto.

MAURICE J. ROSENBERG.
